DECORATIVE BOW STRUCTURE

Bill Y. James, Miami, Okla.

Application May 16, 1950, Serial No. 162,190

2 Claims.

(Cl. 41—10)

1

This invention relates to the decorative arts particularly to gift packaging, the primary object being to provide an inexpensive, easily and quickly formed bow adapted for mounting upon a box or other package and including a plurality of superimposed, elongated loops interconnected and/or joined to the box or tying tape therefor at a single point substantially at the center of the bow.

It is the most important object of the present invention to provide a decorative bow that constitutes in its entirety a plurality of superimposed, radially extending loops, each of which is of itself made from an initially flat, elongated strip of flexible material.

Another important object of the present invention is to provide a bow for decoration purposes including a plurality of loops that are produced by folding an elongated flat strip of flexible material upon itself, and gathering the same together at a mid-point, there being provided a single fastening element adaptable for joining the proximal superimposed ends of the loops and/or connecting the entire bow to either the package or tying tape therefor.

Another object of the present invention is to provide a bow adaptable for decorating packages, made from an initially flat, elongated strip of flexible material such as paper, cloth, cellophane, and having a plurality of perforations extending the entire length thereof, either for the purpose of presenting a bow having a number of loops of differing lengths or a bow having loops of identical length by virtue of exact spacing of the perforations of the strip.

A further object of this invention is to provide a bow construction made from an elongated strip of material provided with equally spaced perforations therealong, the strip having areas of reduced width adjacent each opening respectively to avoid bulkiness at the point of attachment of the loops at the center of the bow and to add to attractiveness.

Other objects of the present invention include the way in which an elongated strip of material is presented and formed to render the same adaptable for cutting shorter strips of material therefrom which may be subsequently folded and joined into loop construction; the way in which novel fastening elements are provided for the loops including tying tape-receiving means, package piercing and locking construction, means to pierce and mount the bow on an auxiliary tape-receiving block; and structure for joining the bow to the tape or to the box by means of adhesive.

Many additional objects will be made clear as the manner of producing the various bows hereof are hereinafter described, reference being had to the accompanying drawing, wherein:

Figure 1 is a perspective view of a package having one form of decorative bow structure of this invention secured thereto.

2

Fig. 2 is a perspective view of the strip material used in forming the bow illustrated in Fig. 1.

Fig. 3 is a fragmentary, elevational view of a modified form of strip material.

5 Fig. 4 is a top plan view of a second form of decorative bow structure.

Fig. 5 is a perspective, stretched-out view of the component parts of the bow illustrated in Fig. 4.

10 Fig. 6 is a sectional view illustrating the manner of mounting any one of the bows of the present invention.

Fig. 7 is a top plan view of another form of decorative bow structure.

15 Fig. 8 is a plan view of the blank used in producing the bow illustrated in Fig. 7.

Fig. 9 is a top plan view of another form of bow utilizing a slightly different type of strip construction.

20 Fig. 10 is a diagrammatical view illustrating the manner of forming another type of bow.

Fig. 11 is a top plan view of the strip of material used to form the bow of Fig. 10.

Fig. 12 is a side elevational view of the fastening element shown in Fig. 6.

Fig. 13 is an end elevational view thereof.

Fig. 14 is an end elevational view of a slightly modified form of fastening means.

30 Fig. 15 is a side, perspective view of a still further form of fastener for the bows.

Fig. 16 is a perspective view of an auxiliary block and fastening construction for the bows.

Fig. 17 is a top perspective view of another type of fastening element.

35 Fig. 18 is a side perspective view of another modified form of fastening means for the bows.

Fig. 19 is a top perspective view of an adhesive type fastener for the bows.

Fig. 20 is a perspective view illustrating one manner of use of the element of Fig. 19.

Fig. 21 is a top plan view showing the manner of using the element of Figs. 19 and 20.

40 Fig. 22 is a top perspective view illustrating another manner of use of the element shown in Fig. 19; and

Fig. 23 is another form of adhesive type, bow fastening element.

45 The various modifications of the decorative bows hereof illustrated in Figs. 1, 4, 7, 9 and 10 respectively, are all of substantially the same character with the exception of that of Fig. 7, in that the same are formed from an initially flat, elongated strip of material. Irrespective of the type of bow that is utilized, the fastening elements illustrated in Figs. 12 to 23 inclusive, are adaptable.

50 Referring first to Figs. 1 and 2, there is illustrated in the latter, a roll 10 of an elongated strip 12 of flexible material preferably of a paper-like nature and of a desired color. The strip 12 is provided with a plurality of equally spaced perforations 14 extending throughout the length of strip 12.

Strip 12 is utilized in producing a bow 16 such as illustrated in Fig. 1 of the drawings and bow 16 is formed in the manner illustrated by Fig. 2. The operator merely forms a plurality of opposed loops 18 in superimposed relationship with the openings 14 in direct alignment for receiving a fastening element 20 or such other fastening element as may be desired and as will herein-after be made clear.

Element 20 has a head 22 and an arrowhead-type of prong construction 24 opposite to head 22 thereof. After the loops 18 are joined by use of the element 20, the latter is forced into one wall of a box or other package 26, as shown in Fig. 6, whereupon the head 22 is turned 90 degrees to automatically lock the prong 24 in place. If desired, the prong 24 may be caused to pass through crossing tapes 28 used as a tying means for box 26.

Obviously, after the loops 18 are formed and the element 20 passed through the aligned openings 14 thereof, loops 18 are turned at various angles with respect to each other upon the shank of element 20 to present the appearance illustrated in Fig. 1 of the drawings.

There is illustrated in Fig. 3, a portion of a modified form of strip 36 of much the same character as strip 12 in that the same is provided with a plurality of spaced openings or perforations 38 at equal distances apart to produce loops of equal size in the same manner as in bow construction 16. The elongated flexible strip 36 however, is provided with a pair of opposed cut-out portions 40 adjacent each opening 38 respectively, to present portions of reduced width at each opening 38. Accordingly, when the tape 36 is placed in use in the same manner as shown in Fig. 2 of the drawings, that part of the completed bow adjacent the centermost fastening element, will be less bulky and will thereby present an even neater appearance than that provided for by use of strip 12.

In Fig. 4 of the drawings, there is illustrated a bow 50 made from the component parts illustrated in Fig. 5. Such parts include a strip 52, a pair of strips 54 and a 4th strip 56. The strips 54 are provided with end tabs 58 of reduced width, each perforated as at 60 and a centermost portion 62 of reduced width having a centrally disposed opening 64 therein. Strip 52 is identical with strip 54 with the exception that the centermost reduced portion thereof has the edges thereof undulated as at 66.

Strip 56 is like strip 54 with the exception that the perforated end tabs 58 are eliminated and the ends of the strip 56 are cut at an angle with respect to the transverse axis of the strip 56. When assembled, the two strips 54 are interposed between strips 52 and 56 and all of the strips with the exception of strip 56, are formed into loops 68. In forming the loops, the perforations 60 of strips 52 and 54 are brought into alignment with the perforations 64 thereof and with the perforation 64 of strip 56. The fastening element such as illustrated as at 20 is utilized to join the four sections of the bow structure 50 and the loops 68 are arranged in the manner illustrated in Fig. 4. Here again the fastening elements 20 may be additionally used to join the bow 50 to a box or the like 26.

It is noted in Fig. 5 of the drawings that the undulations 66 of the strip 52, present the appearance of a knot which may be enhanced pictorially if desired. The strip 56 on the other hand simulates the ends of a tied bow.

The bow 70 illustrated in Fig. 7 of the drawings is produced through use of a blank such as shown in Fig. 8 and designated by the numeral 72. Blank 72 includes a plurality of identical, elongated strips 74 radiating from a common perforated area of integral connections 76. The outermost end of each strip 74 has a tab 78 thereon perforated as at 80 in the same manner as shown in Fig. 5 above described.

In use, the strips 74 are rebent upon themselves to present a number of loops 82 and the perforations 80 are all aligned with the centermost perforation of portion 76 for reception of a fastening element 20. It is preferred further that the strip 56 of Fig. 5, be utilized in connection with loops 82 to again present the "ends" of the tape forming bow 70.

A bow 90 in Fig. 9 of the drawings, is formed from an elongated strip of material similar to that illustrated in Fig. 2 and designated by the numeral 12 except that there is provided a relatively large number of closely spaced perforations 92 extending the full length of the rolled strip. It is seen that through utilization of such strip material, the user may produce a bow of virtually any shape, size or configuration desired. All that is needed is to rebend the material upon itself into a plurality of loops 94 making sure only that each pair of loops has a perforation in alignment with a perforation next below for reception of fastening element 20 or the like.

Bow construction such as shown schematically in Fig. 10 of the drawing, is made from an elongated strip of material 100 such as shown in Fig. 11. Strip 100 is similar in nature to strip 36 in that there is provided a plurality of equally spaced, reduced areas 102 and as shown in Fig. 5, at 66, certain of the areas 102 have the edges thereof undulated as at 104. In lieu of a single perforation such as illustrated at 38 in Fig. 3, each reduced portion 102 is provided with a pair of closely spaced perforations 106. In utilizing the strip 100, the portions between the pairs of perforations 106 are rebent upon themselves to present a plurality of superimposed loops 108 and also rebent to form a line of bend 110 between the perforations 106 of each pair thereof. Accordingly, all of the perforations 106 are in direct alignment for receiving a fastening element 20 and presenting a bow 112. The loops are therefore, disposed in direct superimposed relationship and by cutting the ends of the strip 100 at an angle as at 114, a pair of "ends" 116 will be presented for bow 112.

At this juncture, it is also apparent that the strips 54 and 56 may each be cut from a single length of pre-formed rolled material and in this connection, the strip 100 is virtually adaptable as illustrated for producing the sections 54 and 56 of bow 50.

The fastening element above referred to and designated by the numeral 20, is most clearly illustrated in Figs. 12 and 13 of the drawings and in this instance, a pair of shanks are provided for head 22, each having a prong construction 24 thereon. In lieu of this type of fastening element, a similar fastening 130 may be provided as illustrated in Fig. 14, having a single shank and prong construction 132 thereon.

It is furthermore apparent that any of the bows above described may be interconnected and/or joined with tying tape 28 or box 26 by a conventional fastener 134 such as shown in Fig. 15.

As another possibility, fastening of the bows

may be accomplished through use of an auxiliary block 136 (Fig. 16) having a pair of perforations 138 for threadably receiving a tying tape 140. A brad-like fastening element 142 passing through the perforations of the bow is therewith tacked into the block 136 for holding the bow in place upon the tape 140 and the package which it ties.

The fastener 134 of Fig. 15 may be modified as illustrated in Fig. 17 to produce a fastener 144 having an opening 146 adjacent the outermost end of each leg thereof for threadably receiving a tying tape 148. A knot 150 formed in the tape 148 prevents relative movement between fastening means 144 with its bow thereon and with respect to tape 148. A fastening means 152 in the nature of a brad, has a single shank provided with an opening 154 for threadably receiving a tying tape 156. In this instance, a sharp end prong 159 on the shank of element 152, serves to hold the bow in place by virtue of the point 158 embedding itself in the package.

A strip of bendable material 160 is shown in Fig. 19 of the drawings and having a pair of opposed ears 162 struck therefrom and each provided with a perforation 164. The opposed surfaces of strip 160 are provided with coatings of adhesive 166. In one manner of use of the strip 160, the ears 162 are bent upwardly as illustrated in Fig. 20, the bow is placed between the ears 162 with the aligned perforations thereof in alignment with opposed perforations 164 and a suitable fastening element 168 is used to interconnect ears 162 and the proximal ends of the loops of the bow. Fig. 21 illustrates the way in which the loops are held in position when strip 160 is utilized in this manner. That face of the strip 160 opposite to the laterally extending ears 162, is therewith fastened to tying tape 28 or package 26 by utilization of the adhesive 166 thereon.

Another manner of using the strip 160 is shown in Fig. 22. In this case, one face of the strip 160 is secured to the tying tape or package as just above described and the opposite face is glued to the bow itself after the latter has been formed and secured in place by means of a suitable fastener 170.

In Fig. 23 there is illustrated a bow fastener 200 taking the form of a disc, centrally perforated as at 202 and provided with adhesive (not shown) on the lowermost face thereof. Disc 200 is used in much the same manner as illustrated in Fig. 22 except that perforation 202 receives fastener 170 or the like and serves to attach disc 200 to the bow.

In lieu of the perforations 14, 38, 60, 64, 80, 92 and 106, the various strips may be provided with suitable indicia for designation points to be perforated through use of a fastener such as shown in Fig. 18.

It will be appreciated from the foregoing that there has been provided decorative bow structure that is inexpensive and particularly easy to use even by the most inexperienced operator. Furthermore, a relatively large number of differing types of bows can be made through use of the strips and the various types of fastening means herein disclosed and manifestly, many other types, shapes and configurations can be produced in addition to those specifically disclosed and described above.

In each case a simulated bow can be produced that will maintain its shape and beauty without the need of tying or particular shaping thereof

during its application to a package or the like. Accordingly, it is desired to be limited only by the spirit of this invention as defined by the scope of the appended claims.

Having thus described the invention, what is claimed as new and desired to be secured by Letters Patent is:

1. A decorative bow for use in gift wrapping a package, said bow comprising a single, initially flat, elongated, continuous strip of material formed into a pair of opposed stacks of superimposed, alternately oppositely facing loops, each of said loops having an upper leg, a lower leg and a bight, alternate loops of each stack having open, smoothly arcuate bights disposed remotely from the opposite stack, the remaining loops of each stack having folded bights interlapped with the similar bights of the remaining loops of the opposite stack, the uppermost loop of each stack being one of said alternate loops, the upper leg of each of said remaining loops being common to the immediately overlying alternate loop and forming the lower leg of the latter, each leg of each of said remaining loops being provided with a perforation adjacent the bight of the loop and in alignment with the perforations of the other of said remaining loops of both stacks, the upper legs of said uppermost loops being integral and provided with an opening in alignment with said perforations; and a fastening element extending through said opening and all of said perforations to hold said remaining loops of the pair of stacks in interlapped, tightly superimposed relationship.

2. A decorative bow for use in gift wrapping a package, said bow comprising a single, initially flat, elongated, continuous strip of material formed into a pair of opposed stacks of superimposed, alternately oppositely facing loops, each of said loops having an elongated, upper leg, an elongated, lower leg and a bight, alternate loops of each stack having open, smoothly arcuate bights disposed remotely from the opposite stack, the remaining loops of each stack having folded bights interlapped with the similar bights of the remaining loops of the opposite stack, the uppermost loop of each stack being one of said alternate loops, the upper leg of each of said remaining loops being common to the immediately overlying alternate loop and forming the lower leg of the latter, the lower leg of each of said alternate loops being of the same length as the upper leg thereof, the lower leg of each of said remaining loops being longer than the upper leg thereof, each leg of each of said remaining loops being provided with a perforation adjacent the bight of the loop and in alignment with the perforations of the other of said remaining loops of both stacks, the upper legs of said uppermost loops being integral and provided with an opening in alignment with said perforations; and a fastening element extending through said opening and all of said perforations to hold said remaining loops of the pair of stacks in interlapped, tightly superimposed relationship.
